(57) **CLAIM**

I claim the ornamental design for a torch body, as shown.

DESCRIPTION

FIG. 1 is a back elevational view of a torch body according to the invention.

FIG. 2 is a side elevational view of the torch body of FIG. 1.

FIG. 3 is a front elevational view of the torch body of FIG. 1.

FIG. 4 is a top view of the torch body of FIG. 1.

FIG. 5 is a bottom view of the torch body of FIG. 1.

FIG. 6 is a side elevational view in perspective of the torch body of FIG. 1; and,

FIG. 7 is a front bottom elevational view in perspective of the torch body of FIG. 1.

The broken line portions of the torch are included for the purpose of illustrating environment and form no part of the claimed design.
